N. O. BOND.

WASTE WATER DISCHARGE FOR PORTABLE WASH STANDS.

No. 247,297.

Patented Sept. 20, 1881.

Nathan O. Bond

UNITED STATES PATENT OFFICE.

NATHAN O. BOND, OF FAIRFAX COURT-HOUSE, VIRGINIA, ASSIGNOR OF ONE-HALF TO ADDISON BOYDEN, OF BROOKLINE, MASSACHUSETTS.

WASTE-WATER DISCHARGE FOR PORTABLE WASH-STANDS.

SPECIFICATION forming part of Letters Patent No. 247,297, dated September 20, 1881.

Application filed July 14, 1881. (Model.)

To all whom it may concern:

Be it known that I, NATHAN O. BOND, a citizen of the United States of America, residing at Fairfax Court-House, in the county of Fairfax and State of Virginia, have invented certain new and useful Improvements in Waste-Water Discharges for Portable Wash-Stands; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The purpose of this invention is to avoid the inconvenience attending the use of the ordinary bowl of a portable wash-stand by providing means for enabling a stationary set-bowl to be readily emptied of its contents, after use, into a waste-pail, and providing against overflow of waste-pail, or discharge of water when the waste-pail is not in place; and it consists, first, in the employment of a suitable case or cabinet containing a stationary bowl, of a waste-water receiver to receive the contents of bowl after use, and a flexible pipe connected with the outlet of such bowl and emptying into said receiver, and combined with clamps for pressing it to prevent the escape of the contents of the bowl until the proper time, the compressing device being operated by a knob at the top of the bowl; second, in a swinging gate with ball attached, in connection with clamps, to prevent discharge of water when the waste-pail is nearly full or not in its proper place, and the whole being as hereinafter explained.

The drawings accompanying this specification represent, in Figure 1, a vertical cross-section of my improved stand; Fig. 2, a front elevation of the same, with a portion of the casting broken away; Fig. 3, a detail view of the clamping device.

In these drawings, A represents the case of a wash-stand as composed of a suitable upright frame, covered by a top, B, of marble or other material, having an opening, C, to permit of access to the wash-bowl D below, this bowl being permanently secured in place in the upper part of the structure, and the space below it

being occupied by partitions and drawers, if necessary.

In carrying out my invention I prefer my waste-water receiver to be made long and narrow, with square corners, and in the accompanying drawings have so represented it. This receiver is to be provided with a bail, by which it may, after being removed from the cabinet, be carried, after the manner of an ordinary water-pail, to be emptied of its contents, one end being formed into a spout or nose to facilitate such emptying of its contents. The bowl D has a central outlet, d, at bottom, and with this outlet I connect one end of a flexible tube, e, the other end of which terminates at a point over the waste-water receiver, this pipe serving, when unobstructed, to carry waste water from the bowl to the receiver.

To provide economical, durable, and effective means of closing the outlet of the bowl until it is desired to empty the latter of its contents, I pass the tube e between a gate or clamp, f, composed of cast-brass or other material, which is kept compressed by the spring g sufficiently to prevent the waste of water through the tube until opened by the lever h, connecting with knob i at the top of the bowl. After use of the bowl the knob i is pressed, which opens the clamp f and permits the water to escape through the pipe e into the waste-pail, provided the waste-pail is in position and not too full.

In order to prevent the escape of water when the waste-pail is removed or when it is nearly full, I use the following device: Near the back of the case, and in the path of the waste-pail, between the partitions k k, I fix a swinging gate, l, pivoted at each end, and carrying an arm, m, fixed on its upper side, and provided at its forward end with a small wooden ball or float, n. This ball is connected by a chain, n', to a weighted stop, e', which swings between two ears on the outer end of the clamp-lever h, resting in its raised position against a spring, o, on the lower side of the clamp-lever h.

The operation of this device is as follows: As the waste-pail is slid into position between the partitions k k the nose strikes the gate l and raises it to a horizontal position, which allows the ball n to drop into the position shown

in Fig. 1 and brings the weight of the ball through the chain-connection n' on the longer arm of the weighted stop e' and raises the shorter or weighted arm f' against the spring o , forming the bottom of the recess q , in which the knob-spindle p rests, locking it in that position. While the parts are in this position any pressure on the knob i will open the clamp f , allowing the discharge of water from the bowl. When sufficient water is collected in the waste-pail to raise the ball n and loosen the chain n' the weight of the short arm of the stop e' will cause it to drop out of locking position and free the end of the spring o , as shown by dotted lines in Fig. 3, and any pressure of the knob i will then act only on the spring o and will not be communicated to the clamp, thus preventing any overflow of the waste-pail.

The removal of the waste-pail would obviously have the same effect in relieving the chain of the weight of the ball through the swinging gate l , and thus prevent any discharge of waste-water if the pail is not in position. In either case the operation is mainly the same.

The construction of my clamping device is clearly shown in Fig. 3, and consists in a collar, 1, fitting closely around the outlet-tube d , and serving to firmly secure the flexible tube in position on the said tube d . On this collar is fastened in any suitable manner the arm 2, which forms one of the jaws of the clamp. On each side of the collar is fastened a spring, g , and to the free end of the spring the other jaw

of the clamp 3 is secured in such a manner that the opening of the jaws will be against the force of the spring, the springs g thus serving to keep the jaws of the clamp tightly closed against the flexible tube e . To the jaw 3 is connected the arm h , through which the clamp is operated.

The spindle passes through the bowl D at opening x , and is provided with a knob, i , the springs g and o always bringing it back to position after it has been pressed down. 45

Having thus described my invention, what I wish to claim, and desire to secure by Letters Patent, is—

1. In combination with the flexible discharge-pipe e , the collar 1, jaws 2 3, spring g , and lever h . 50
2. The discharge-pipe e , the clamps for closing the same, and the lever h , in combination with the float n , connected to the weighted arm e' , the spring o , and the spindle p .
3. In combination with a flexible discharge-tube and spring-jaws for compressing the same, a receiving-tank and means for automatically preventing the compressing-jaws from opening to admit more water to the tank. 55
4. The combination of the lever h , having 60 the hole q , of the weighted arm e' , the spring o , the automatic float, and the spindle p .

In testimony whereof I affix my signature in presence of two witnesses.

NATHAN O. BOND.
